UNITED STATES PATENT OFFICE

2,452,269

EXPLOSIVE PROJECTILE

Donald Guilford Stine, Mount Carmel, Pa.

Application March 8, 1944, Serial No. 525,557

2 Claims. (Cl. 102—62)

1

This invention relates to an explosive projectile or shell designed primarily for use in antiaircraft fire. An object of the invention is to provide a projectile of this type having an increased area of efficiency and which will not pass through an objective without exploding.

A further object is to provide a shell or projectile with fins adapted to move outwardly in planes radiating from the shell after emerging from the gun and prior to reaching the objective, these outwardly movable elements constituting means for retracting firing pins and for subsequently releasing them at the time of impact so that the charge will be exploded by the action of the released pins.

A still further object is to provide the projectile with safety means to prevent release of the firing mechanism while the projectile is being handled.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is an elevation of the projectile, the parts being shown held against premature actuation.

Figure 2 is a section on line 2—2, Figure 1, a portion of one of the fins being shown by broken lines in released position and the pin associated therewith being shown by broken lines in lifted position and by full lines in firing position.

Figure 3 is a view showing the rear or butt end of the projectile.

Figure 4 is a section on line 4—4, Fig. 2.

Referring to the figures by characters of reference, 1 designates the body portion of the shell which can be provided, at its tapered front end with the usual timer indicated generally at 2. A cylindrical butt member 3 has a screw-threaded extension 4 which is screwed into the body portion 1, the outer surface 5 of this head being substantially flush with the corresponding surface 6 of the body portion 1. A wide annular channel 7 is provided in the outer surface of the meeting portions of the two members 1 and 3 of the shell and mounted to slide within this channel is a locking ring 8 which can be secured against movement by means of a set-screw 9.

2

Formed within that end portion of the member 3 abutting against the member 1 are bores 10 extending through the closed end 11 of the member 3 and holding shells 12 having primary charge chambers 13 which open into the interior of member 3 through apertures 14. A cap 15 is positioned in each of the shells between opening 14 and the member 1 and mounted in each shell is a firing pin 16 having a collar 17 positioned to receive thrust from one or more springs. In the drawing a coiled spring 18 and a bow spring 19 are provided for this purpose, both springs being mounted on the firing pin and thrusting at one end against one end of shell 12 and at its other end against the collar 17. It will be noted that the springs 18 and 19 serve to hold the firing pins normally pressed firmly against the caps 15. However, when the firing pins are retracted, as hereinafter explained, the springs 18 and 19 will be compressed with the result that when the firing pins are released, these compressed springs will be released and the energy stored therein will be sufficient to drive the firing pins forcibly against the caps 15 to explode them.

Longitudinal grooves 20 are provided in the outer surface of the member 1 and the firing pins 16 extend into the respective grooves where they are provided with laterally extended lugs 21.

Pivotedly mounted within each groove 20 is an elongated fin 22. A pivot pin 23 is located adjacent to one of the firing pins, so as to connect each fin to the member 1 and extending from each fin adjacent to its pivot pin, is a lifting finger 22'. When the fins are fully seated in the grooves 20, their outer edges are flush with the corresponding surface of the member 1.

That portion of each fin which is normally exposed in the annular groove 7, is normally flush with the inner wall of the groove and is adapted normally to be engaged by the ring 8 so that the fins thus are held against outward swinging movement relative to the body portion of the projectile.

The members 1 and 3 are filled with an explosive indicated at 24 and an explosive also fills the primary charge chambers 13.

When the projectile is placed in a gun preparatory to being fired, the set-screw 9 or other fastening means is loosened and ring 8 is swung from the position shown in Fig. 1 downwardly to the other extreme position in the groove 7. The wall of the gun bore will of course keep the fins 22 from swinging outwardly during the loading operation. When the gun is fired the arms 20 will be swung outwardly relative to the member 1 by springs 25 located between the fins and the

inner walls of the grooves 20. Thus the diameter of the path of the projectile is increased by the combined lengths of the opposed laterally extended fins. As the fins swing outwardly the lifting fingers 22' thereon will come against the lugs 21 and pull the firing pins against the action of the springs 18 and 19 as shown by broken lines at the left of Figure 2. These springs are of such strength as to limit the swinging movement of the fins while travelling through the air but, on striking an objective, the fins upon meeting the resistance offered thereby, will be pressed back to overcome the restraining action of the springs with the result that the lifting fingers 22' will be snapped past the lugs 21, thereby releasing the springs so that the energy stored by the traction of the springs will be released and the shifted firing pins thus will be free to shift back toward their normal positions, one of which has been indicated at the right of Figure 2, with the result that the violent contact of each firing pin against the explosive charge will be sufficient to fire the charge. Consequently there is no danger of the projectile passing through an objective without exploding.

For the purpose of preventing injury to the rifled surface of a gun from which the projectile is being fired, it is designed to provide each fin 22 with laterally extending wings 25' seated in lateral extensions 26 of the grooves 20 so that the grooves in the gun bores will be bridged thereby.

The projectile can be provided, near its butt end with one or more expansion rings 27.

It will be noted that parts of this projectile can be assembled readily inasmuch as the shells 12 containing the primary charges and the caps can be screwed into position after the other parts have been assembled and after the fins 22 have been lapped in folded position by the ring 8 and the set-screw 9.

What is claimed is:

1. An explosive shell including main and butt members cooperating to provide an explosive chamber, there being longitudinal grooves in the main member and longitudinal bores in the butt member opening into the grooves, said grooves and bores being substantially aligned, a shell removably seated in each bore, each shell being in

communication with the explosive chamber, a cap in each shell, a yieldingly restrained firing pin in each shell normally in close proximity to the cap, and separate means movably mounted in the grooves for actuating the respective firing pins to explode the caps, said means including fins pivotally mounted in the grooves, lifting fingers carried by the fins and positioned for movement into engagement with and past the firing pins, and a spring interposed between each fin and the main member for projecting the fin outwardly from the groove.

2. An explosive shell including main and butt members cooperating to provide an explosive chamber, there being longitudinal grooves in the main member and longitudinal bores in the butt member opening into the grooves, said grooves and bores being substantially aligned, a shell removably seated in each bore, each shell being in communication with the explosive chamber, a cap in each shell, a yieldingly restrained firing pin in each shell normally in close proximity to the cap, separate means movably mounted in the grooves for actuating the respective firing pins to explode the caps, said means including fins pivotally mounted in the grooves, lifting fingers carried by the fins and positioned for movement into engagement with and past the firing pins, a spring interposed between each fin and the main member for projecting the fin outwardly from the groove, and means adjustably mounted on the shell and positioned normally to hold the fins against swinging movement.
